APPARATUS FOR FILLING AND COMPACTING MATERIAL IN BAGS AND HAVING A RETRACTABLE BAG BOTTOM ABUTMENT MEMBER

Harold V. Kindseth, Minneapolis, Minn., assignor to Bemis Bro. Bag Company, Minneapolis, Minn., a corporation of Missouri

Application April 9, 1949, Serial No. 86,552

8 Claims. (Cl. 226—55)

1

This invention relates to new and useful improvements in apparatus adapted for settling or compacting finely ground granular material in containers during the operation of filling the containers.

An object of the present invention is to provide an apparatus for settling and compacting material in a flexible walled bag while the bag is pendently supported in mid air beneath a packer tube.

A further object is to provide an apparatus of the character disclosed comprising a suitable bag holder adapted to grip the bag top walls and support the bag in position over the discharge end of a packer tube, and means being provided for imparting a shaking movement to the bag while suspended below the packer tube to receive a charge, thereby to cause the material to become firmly compacted in the bag.

A further object is to provide an apparatus for compacting comminuted material in flexible walled containers, comprising a bag holder adapted to be fitted over the discharge end of a packer tube and provided with suitable jaws for gripping the walls of a bag top to secure the bag in position under the packer spout to receive a charge, and a mechanism being operatively connected to the bag holder for imparting a shaking motion thereto in a vertical plane, during the filling operation, including a movable platform adapted to be intermittently engaged by the bag bottom as the bag is rapidly moved up and down by the shaker mechanism, and whereby the bag body is constantly being bounced up and down on said platform to cause the material to become firmly compacted therein, after which the platform is swung to an inoperative position to permit the filled bag to be delivered onto a suitable conveyor.

A further object is to provide an apparatus of the class described comprising a pneumatically operated bag holder adapted to grip the walls of a bag top to support the bag in position on a packer tube, and means being provided for imparting a vibratory action to the bag holder in an up and down direction, whereby the bag bottom may be bounced up and down on a pivoted platform supported under the packer tube, said platform being operatively associated with the vibrating mechanism, whereby when the bag has received its full charge, and the operations of the vibrating mechanism and the packer tube are interrupted, the bag holder is actuated to release the bag and simultaneously the platform is swung out of the way of the bag to permit the filled bag to be delivered into a suitable conveyor.

Other objects of the invention reside in the simple and inexpensive construction of the apparatus whereby it may be manufactured at small cost; in the means for movably supporting

2

the bag holder on the packer tube whereby the bag holder may be freely moved up and down on the packer tube by the vibrating mechanism; in the arrangement of the bag top gripping jaws and the parallel arms for supporting the bag holder and to one of which the bag shaking means is connected; in the specific construction of the means for swinging the platform into and out of operative relation with respect to the bag body; and in the provision of a portable shaker of the class described which is highly efficient and practical in operation, and is self-contained, whereby it may be conveniently moved about from one place to another, when necessary.

These and other objects of the invention and the means for their attainment will be more apparent from the following description taken in connection with the accompanying drawings.

In the accompanying drawings there has been disclosed a structure designed to carry out the various objects of the invention, but it is to be understood that the invention is not confined to the exact features shown, as various changes may be made within the scope of the claims which follow.

20 In the drawings:

Figure 1 is a side elevational view of the apparatus showing a bag suspended from the bag holder with its lower end out of engagement with the abutment platform;

Figure 2 is a view similar to Figure 1 showing the bag holder in its lowered position with the bag bottom engaging the platform;

Figure 3 is a view similar to Figures 1 and 2 but showing the abutment platform in inoperative position to permit the filled bag to be delivered onto the receiving conveyor;

Figure 4 is a sectional plan view on the line 4—4 of Figure 1;

Figure 5 is a sectional plan view on the line 5—5 of Figure 1;

Figure 6 is a detail sectional view on the line 6—6 of Figure 2; and

Figure 7 is a fragmentary sectional view on the line 7—7 of Figure 2, showing the means for adjustment.

Supporting frame

The novel apparatus herein disclosed is shown comprising a suitable frame, preferably of structural steel, shown comprising front and rear base members 2 and 3, respectively, and side frame members 4 which may be suitably secured together as by welding, to provide a very substantial and rugged structure. Upright frame members 5 and 6 are provided at the front and rear of the apparatus and may be secured together by suitable tie members 7, 8, 9 and 11. The supporting frame may include other cross members 12, 13 and 14, the latter being shown se-

cured to uprights 15, interposed between the horizontal frame members 9 and 11.

Bag holder

An important feature of the present invention resides in the means provided for supporting each bag in filling relation to the discharge end of the packer tube 16 of a conventional packer, not shown, during the operation of filling each bag. The packer tube 16 is disposed at the front of the machine frame as best shown in Figures 1, 2 and 3.

The bag holder generally designated by the numeral 17, is shown comprising a tubular member 18 fitting over the lower end portion 16 of the packer tube. Suitable sealing means, not shown, is provided for preventing spouting of the material from the bag top between the member 18 and the periphery of the bag top during the filling operation.

Opposed bag holding jaws 19 partially surround the cylindrical portion 18 of the bag holder, and are shown supported by parallel links 21 and 22. The links 22 are secured to horizontally disposed arms 23 supported on suitable pivots 24 shown in the lower portion of a member 25, mounted in the lower portion of a member 25, forming a part of the bag holder. The arms 22 and 23 at each side of the bag holder 17 cooperate to provide a bellcrank. The upright arms 22 of the bellcranks are secured to the jaws 19, and the swingable ends of the horizontal arms 23 are secured to suitable toggles generally designated by the numeral 26.

The two toggles 26 are preferably arranged to be operated simultaneously by pneumatic means, shown comprising an air cylinder 27 having one end connected to one of the toggles 26, and a piston being mounted within the cylinder 27 and having a piston rod 28 operatively connected to the other toggle, as clearly illustrated in Figures 1, 2 and 3. Thus, when air is admitted into the cylinder 27 through the air supply conduit 29, the piston rod 28 is retracted as shown in Figures 1 and 2, thereby to simultaneously actuate the toggle mechanisms 26 to cause the bag holder jaws 19 to firmly grip the walls of the bag, as best illustrated in Figure 2. When the flow of air to the cylinder is reversed, the jaws 19 are actuated to release the bag top walls. The air supply conduits 29 and 31 are connected to a suitable air supply and control means, not shown in the drawings.

Bag holder shaking means

The bag holder shaking means is clearly illustrated in Figures 1, 2 and 3, and operates to impart an up and down shaking movement to the bag holder and a bag supported thereon. An important feature of the present invention resides in grasping each bag by its top walls and suspending it from the bag holder while rapidly shaking it up and down to settle its contents.

The bag holder 17 is supported at the outer ends of spaced pairs of parallel arms 32 and 33 having pivotal connections with the bag holder at opposite sides thereof, as shown at 34 and 35. The opposite ends of the arms are shown connected to shafts or pivots 36 and 37 supported in brackets 38 and 39, respectively, secured to the upper end portions of the upright frame members 6.

The means for imparting a vibratory or shaking motion to the bag suspended from the bag holder is shown comprising a cross shaft 41 mounted in bearings 42 and having a suitable

crank pin 43, adjustably secured thereto by such means as the adjusting screw 44, shown in Figure 7. A pitman 45 has one end engaging the crank pin 43 and its opposite end a tie member 40, interposed between and secured to the lower arms 33 of the bag shaking mechanism. The cross shaft 41 is shown driven from a suitable motor 46 by a chain 47 having a running connection with a sprocket 48 secured to the shaft 41.

Abutment platform

To facilitate quickly settling the material in the bags, an abutment platform, generally designated by the numeral 49, is mounted for pivotal movement about the axis of a cross shaft 50. The shaft 50 is supported in the outer ends of a pair of arms 51 secured to a shaft 60, shown mounted in suitable brackets secured to the cross member 13 of the supporting frame. Rivets 63 secure the shaft 50 against relative rotation in the arms 51. The abutment platform 49 is shown comprising spaced bag bottom engaging members 52 and 53, secured to triangularly shaped brackets 54. The brackets 54 have their upper rear portions pivotally supported on the shaft 50, and their lower forward portions to arms 55 having their rearwardly directed ends secured to a horizontal shaft 56, mounted in suitable bearings 57, shown in Figures 1, 2 and 3.

The arms 55 have slidable connections with the brackets 54, and to accomplish this, each bracket has an elongated upright slot 58 in its rear portion 59 adapted to receive suitable slides 61 mounted on a shaft 62 supported in the front ends of the arms 55, as perhaps best illustrated in Figure 6. The slides 61 are preferably rectangular in configuration and are adapted for sliding movement in the slots 58. Each slide 61 preferably has a flange 64 adapted to engage one side of its complementary bracket 54, and a washer 65 is mounted on the shaft 62 at the opposite side of each bracket 54. Collars 66 are secured to the ends of the shaft 62 adapted to retain the movable parts in position thereon, it being understood that a slide 61 is provided at each end of the shaft adapted for movement in the slots 58 in the brackets 54, as will subsequently be described. The rearwardly directed ends of the arms 55, as hereinbefore stated, are secured to a horizontal shaft 56 adapted for direct movement with said arms.

To assure that the platform 49 is quickly swung to its out of the way position when the bag has been filled and is about to be released from the bag holder 17, as shown in Figure 3, a suitable cam 67 is mounted on the shaft 50 between the triangular brackets 54, as shown in Figure 6. Suitable means, such as a rivet 68, secures the cam against relative rotation on the shaft 50, whereby it is retained in the same relative position with respect to the arms 51, regardless of the positions of said arms.

Operating means for platform

The means for automatically operating the platform 49 is best shown in Figures 1, 2, 3 and 5, and comprises a cylinder 69, the upper head 71 of which is shown provided with lugs 72 apertured to receive a pivot pin 73 mounted in a bracket 74 secured in fixed position upon the supporting frame of the machine.

A piston 75 is mounted for reciprocal movement in the cylinder 69, and has a rod 76 projecting from the lower end thereof. The lower end 75 of the piston rod 76 is connected to an arm 77 by

a suitable pivot pin 78, and the arm 77 is secured to one end of the shaft 56 and is operable therewith as a unit. Fluid supply conduits 79 and 81 are connected at one end of the upper and lower ends of the cylinder 69 and have their opposite ends connected to a conventional fluid control valve, not shown, which in turn may be connected to a supply of fluid under pressure, not shown in the drawings.

Operation

In the operation of the novel bag packer herein disclosed, the mouth of an empty bag is fitted over the packer tube 18, as shown in Figure 1 with its upper marginal edges of the bag top walls being inserted between the jaws 19 of the bag holder and the upper cylinder portion 82 of the tubular member 18. When the bag reaches the position shown in Figure 1, the operator engages a control device (not shown), which causes the air supply means to deliver air to the cylinders 27 and 69, whereby the toggle devices 26 are simultaneously actuated to move the jaws into gripping engagement with the bag top walls, and at the same time the piston rod 76 is moved downwardly to restore the platform 49 to its operative position, shown in Figures 1 and 2.

When the empty bag has thus been secured to the packer tube, the current supply circuit for the motor, not shown, is closed, whereupon the shaft 41 is rotated by a chain drive 47 to cause the crank pin 43 to operate and impart a vibratory motion to the bag holder 17 and the bag secured thereto, as a result of the pitman 45 being operatively connected to the arms 33 of the bag holder by the member 40. The crank pin imparts an up and down movement to the bag holder in rapid succession, whereby the bottom of the bag is bounced up and down on the platform 49, thereby to cause the contents of the bag to become firmly settled therein.

When the contents of the bag has thus become firmly compacted in the bag body, and the correct weight of material has been delivered thereto, the supply of current to the motor is automatically interrupted, and simultaneously, the feeding of material from the packer tube 16 into the bag is interrupted, as is well known. Such interruption of the packer tube will cause actuation of the toggles 26, whereby the bag holder jaws 19 are actuated to release the bag top. Simultaneously, the piston rod 76 is retracted, thereby upwardly swinging the arms 55 from the positions shown in Figure 1 to the upright position shown in Figure 3, whereby the slides 61 travel upwardly in the slots 58, as will be understood by reference to Figures 2 and 3.

An important feature of the invention resides in the provision of the cam 67, which is secured in fixed relation to the shaft 50 and is engaged by a roller 83, rotatably supported on the intermediate portion of shaft 62, as best illustrated in Figure 6. The contour of the working face of cam 67 is such that when the roller 83 engages the face of the cam, the cam, including the outer ends of the arms 51, are quickly swung upwardly to the positions shown in Figure 3, causing the platform 49 to be moved out of the path of the bag so that the latter may drop by gravity onto the conveyor belts 84. The conveyor belts 84 are preferably inwardly canted, as shown in Figures 1, 2 and 3, so that a bag may be transported thereby without danger of the bag tipping over.

The machine may readily be adjusted for bags of different heights by simply adjusting the position of the platform 49 with relation to the bot-

tom of the packer tube 16. To thus adjust the machine for bags of different heights, spaced posts 85, preferably square in cross section, slidably supported in guide brackets 86, whereby the posts 85 are adapted for relative vertical movement.

Each post 85 is interiorly threaded longitudinally to receive adjusting rods 87 having their lower ends secured in suitable bearings 88, secured to the machine frame. A chain drive 89 operatively connects together the threaded rods 87 for simultaneous rotation, thereby to facilitate translating the posts 85 in their guides 86. The upper ends of the posts 85 engage the ends of the arms 51 and provide stops for their downward movement, whereby the platform will thereby come to rest at a selected position with respect to the bottom of the packer tube 16.

An operating shaft 91 has one end supported in a bracket 92 and has a pinion 93 secured thereto which meshes with a bevel gear 94 secured to one of the threaded rods 87, as clearly illustrated in Figure 2. An operating wheel or member 95 is secured to the other end of the operating shaft 91 whereby the operator of the machine may readily rotate the shaft 91 to adjust the position of the platform 49 with respect to the packer tube, as will be understood with reference to Figure 2.

The various control elements and devices utilized for controlling the operation of the apparatus have not been shown in the drawings, as they are of well known construction and may be arranged in any desired manner to obtain the desired results. They are preferably so arranged that the machine will go through a complete cycle of operation, each time a bag is fitted over the packer tube and secured thereto by the bag holder jaws 19.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

I claim as my invention:

1. In an apparatus of the class described, a supporting frame, a bag holder for supporting a bag in position under the discharge end of a packer tube to receive a charge, an arm having one end pivoted to the frame and its opposite end to the bag holder, means operatively connected with said arm for imparting pivotal movement thereto in rapid succession, thereby to impart a shaking movement to the bag suspended from the bag holder, a bag bottom engaging member, a guide link having one end pivoted to the machine frame and its opposite end to the upper portion of said member, a relatively shorter link having one end pivoted to the machine frame and its opposite end to said member, said shorter link having a sliding connection with said member, and means for actuating said shorter link to move the member into or out of bag engaging position.

2. In an apparatus of the class described, a supporting frame, a bag holder for supporting a bag in position under the discharge end of a packer tube to receive a charge, an arm having one end pivoted to the frame and its opposite end to the bag holder, means operatively connected

with said arm for imparting pivotal movement thereto in rapid succession, thereby to impart a shaking movement to the bag suspended from the bag holder, a bag bottom engaging member normally positioned beneath the bag body, a guide link having one end pivoted to the machine frame and its opposite end to the upper portion of said member, a relatively shorter link having one end pivoted to the machine frame and its opposite end to said member, said shorter link having a sliding connection with said member, a cam mounted in fixed relation to said relatively longer link, and means carried by the outer end of the shorter link adapted to engage said cam and thereby retract said member from its operative position beneath the bag bottom, when the bag has been filled and is released from the bag holder.

3. In an apparatus for filling flexible-walled bags and settling the contents therein, a frame, a bag holder comprising a cylindrical member adapted to be fitted over the discharge end of a conventional packer tube, opposed jaws on said cylindrical member operable clampingly to secure the upper end walls of the bag body thereto, toggle means for simultaneously actuating said jaws, a pair of arms having their corresponding ends horizontally pivoted to the frame and their opposite ends to the bag holder, a pair of arms for supporting the bag holder, said arms being horizontally pivoted at one end to the machine frame and pivoted at their other ends to the bag holder, fluid-operated means for simultaneously actuating said toggle means for operating said jaws, a pitman having one end pivotally connected to said arms, crank means for operating the pitman to impart a vibratory up and down motion to the bag holder to settle the contents of a bag supported thereon during the filling thereof, a retractable abutment member adapted to be positioned to be engaged by the bottom of the bag supported in said holder whereby the bag bottom will intermittently engage said abutment member in rapid succession, when the supporting arms for the bag holder are moved up and down, thereby to cause the material to become settled firmly in the bag during the filling operation, links mounted for pivotal movement in the supporting frame and having their swingable ends operatively connected to said retractable member, upwardly concave conveyor means positioned beneath said retractable abutment member, and means for actuating said links to automatically retract said abutment member from a position above the conveyor when the filled bag is released from the bag holder, thereby to permit the bag to be delivered directly onto said upwardly concave conveyor belt.

4. In an apparatus for filling containers and settling the contents therein, a supporting frame, a holder adapted to be fitted over the discharge end of a conventional packer tube, means operable to secure a container thereto, means for vibrating said holder to settle the contents in the container, a retractable abutment member adapted to be positioned to be engaged by the bottom of the container, links each having one end mounted for pivotal movement in the supporting frame and having their swingable ends operatively connected to said abutment member, a second pair of links pivoted on the machine frame and having their swingable ends slidably connected to the abutment member, cam means movable with said first links, and means carried by said second links for engaging said cam means

70 to effect retraction of said abutment member when the filled bag is released from the bag holder.

5. In an apparatus for filling flexible-walled bags and settling the contents therein, a supporting frame, a bag holder adapted to be fitted over the discharge end of a conventional packer tube, means for clampingly secure the upper end walls of a bag body thereto, means for imparting an up and down shaking motion to said bag holder, a retractable abutment member adapted to be positioned to be engaged by the bottom of the bag, upper parallel links each having one end pivoted in the supporting frame and having their other ends pivoted to said retractable abutment member, slides disposed in said abutment member, a second pair of links each having one end pivoted in the supporting frame and having their other ends connected to said slides, and means operable to adjustably position said abutment member relative to the bottom of the bag supported in said holder.
